UNITED STATES PATENT OFFICE.

NATHAN C. CHAPMAN, OF DETROIT, MICHIGAN.

HYDROCARBON-BURNER.

1,378,323.

Specification of Letters Patent. Patented May 17, 1921.

Application filed August 18, 1919. Serial No. 318,103.

To all whom it may concern:

Be it known that I, NATHAN C. CHAPMAN, citizen of the United States, residing at Detroit, county of Wayne, State of Michigan, have invented a certain new and useful Improvement in Hydrocarbon-Burners, and declare the following to be a full, clear, and exact description of the same, such as will enable others skilled in the art to which it pertains to make and use the same, reference being had to the accompanying drawings, which form a part of this specification.

My invention relates to hydrocarbon burners, shown in the accompanying drawings and more particularly described in the following specification and claims.

As ordinarily constructed burners of this type consist of an inner and an outer perforated chimney spaced apart and supported upon a fuel trough, an asbestos lighting ring being lodged in the fuel trough that it may be saturated with the fuel and then ignited to convert the oil subsequently delivered to the burner into gas. An outer fuel ledge has also been employed in some cases connected with the fuel trough, into which the fuel pipe discharges.

One of the objects of the present invention is to simplify the construction,—reduce the manufacturing cost,—provide a burner adapted to rapidly convert the liquid fuel into gas, and so construct it that it may be readily cleaned when required.

One feature of the invention is to construct the inner perforated lower section of the chimney integral with the fuel trough that the heat may be more readily conducted thereto, the outer imperforated wall of the trough being relatively low that the trough may be readily cleaned upon removing the outer perforated chimney, the latter having an offset ledge or flange to adapt it to be supported by the outer wall of the trough.

The outer perforated chimney will admit air to the lighting ring but is supported by the outer relatively low wall of the trough out of contact with the fuel oil, that it may not be coated thereby.

Another feature of the invention is the annular wind shield adapted to support the outer drum but which serves to protect the burner from side drafts, and on which rests the fuel trough of the burner.

Another feature of the invention consists in a centrally disposed bolt for each burner to hold the several sections of the burner to-

gether and for securing the burner upon a longitudinal rod or member of the stove frame;—the construction being such that any number of burners may be secured to the frame whereby a stove of any desired size may be quickly produced.

With the foregoing and other objects in view which will appear as the description proceeds, the invention resides in the combination and arrangement of parts and in the details of construction hereinafter described and claimed, it being understood that changes may be made in the precise embodiment of the invention herein disclosed without departing from the spirit of the same.

In the drawings accompanying this specification:—

Figure 1 is a side elevation of an oil stove showing a plurality of burners installed therein.

Fig. 2 is a side elevation of the burner with the outer drum broken away to show a portion of one of the perforated chimneys.

Fig. 3 is a vertical cross-sectional view through the burner secured to the inverted channel-iron forming part of the stove frame.

Fig. 4 is a horizontal cross-sectional view on line 4—4 of Fig. 3.

Referring now to the letters of reference placed upon the drawings:—

A, denotes an inner perforated cylindrical chimney formed in sections with perforated partition walls A', between each section. A², indicates the lower section provided with an integral fuel trough B, having an annular depression or groove B' in its lower wall adjacent to the outer wall C;—the latter wall being relatively low that the trough may be easily cleaned when required.

D, indicates an outer perforated chimney, supported in spaced relation to the inner chimney A, by a recessed flange D', in its lower edge which overlaps the outer wall C, of the fuel trough.

E, indicates an annular wind guard, consisting of an outer imperforated flanged wall E', having a perforated bottom E², through which air passes to the burner, and an imperforated flanged ring E³, forming the inner wall of the wind guard,—on which is mounted the chimney A. F, is a drum supported on the flanged wall E', of the wind guard. G, indicates an inverted longi-

tudinal channel bar secured to the end frames H, of the stove for supporting the several burners. I, denotes a centrally disposed bolt projecting downwardly through 5 the respective sections of the inner chimney A, and also the wind guard E, of each burner to secure the burners in spaced relation to each other upon the channel iron G;—any number of burners being secured to the 10 bar as may be required. J, indicates an asbestos lighting ring provided with a suitable bail J', to facilitate its removal when it is desired to ignite the oil saturating the ring. The ring J, rests upon the platform of the 15 fuel trough B, above the depression or groove B'. K, is a valve for controlling the delivery of oil through the pipe L, to the burner.

To ignite the burner, the valve is opened 20 so that a small quantity of fuel may flow into the trough and saturate the asbestos ring.

A flame is then applied to the ring which causes the fuel to ignite, and the inner 25 chimney and its integral fuel trough to be quickly heated, thereby converting the liquid fuel into gas which is consumed between the perforated inner and outer chimneys.

Upon the fuel trough becoming heated 30 sufficiently to form a gas the valve may be adjusted to admit only sufficient oil to fill the depression or groove B'—this volume of fuel is so proportioned that it will quickly 35 vaporize forming a blue flame with intense heat.

By constructing the outer integral wall of the fuel trough relatively low, the outer chimney may be removed and the burner readily cleaned.

40 The use of the wind guard or shield E, protects the flame from side draft, while the perforations in the bottom of the wind guard provide for the admission of air to support combustion.

45 The centrally disposed bolt I, provides a simple means of securing the several sections of the burner together to form a single unit which may be readily secured to the channel or other suitable supporting bar of 50 the stove flame, whereby a stove of any required number of burners may be quickly constructed.

Having thus described my invention, what I claim is:—

55 1. In a hydro-carbon burner, the combination of an inner perforated chimney consisting of superimposed sections of pipe, the lower section of the chimney being provided with an integral annular trough hav-

ing a relatively low outer wall, to permit 60 of ready access to the trough, said trough having an annular groove in its floor adjacent to its outer wall, an outer perforated chimney adapted to be supported upon the outer wall of the fuel trough, a wind guard 65 consisting of an inner perforated flanged ring adapted to support the chimney and an outer flanged perforated ring having a perforated horizontal wall upon which the inner flanged ring is adapted to rest, a cone-shaped drum supported upon the outer flanged wall of the ring, and a valve controlled means for delivering liquid fuel to the trough.

2. In a hydro-carbon burner, the combination of an inner perforated chimney formed of superimposed sections of pipe, the lower section of pipe constructed with an integral annular fuel trough having a relatively low imperforated outer wall, an 80 outer perforated chimney adapted to be supported upon the outer wall of the fuel trough, an annular wind guard having imperforated side walls spaced apart with a lower connecting perforated wall for the 85 passage of air, a bar for supporting the burner; and a central bolt extending through the several sections of the chimney, the wind guard, and the supporting bar, for 90 securing said first named parts to the supporting bar.

3. In a hydro-carbon burner, the combination of an inner perforated chimney formed in sections and bridged by perforated partition walls, the lower section constructed with an integral annular fuel trough having a relatively low outer wall and an annular groove in the floor of the trough adjacent to the outer wall, a perforated outer chimney adapted to be supported upon the outer wall of the trough, a wind guard consisting of an inner imperforated flanged ring adapted to support the chimney and an outer flanged imperforated ring having a perforated horizontal 95 wall upon which the inner flanged ring is adapted to rest, a cone-shaped drum supported upon the flanged outer wall, a supporting bar for the burner, and a central bolt extending downwardly through the sections of the chimney and the guard to secure 100 the several parts to the supporting bar.

In testimony whereof, I sign this specification in the presence of two witnesses.

NATHAN C. CHAPMAN.
